C. SPEARMAN

APPARATUS FOR ORE SEPARATION

Filed Sept. 18, 1919

UNITED STATES PATENT OFFICE.

CHARLES SPEARMAN, OF WESTMOUNT, QUEBEC, CANADA.

APPARATUS FOR ORE SEPARATION.

Application filed September 18, 1919. Serial No. 324,310.

To all whom it may concern:

Be it known that I, CHARLES SPEARMAN, a subject of the King of Great Britain, residing at Westmount, in the Province of Quebec, Dominion of Canada, have invented certain new and useful Improvements in Apparatus for Ore Separation, of which the following is a specification.

This invention relates to the extraction or recovery of minerals from their ores and the purification of concentrates. More specifically, the invention relates to improvements in apparatus designed particularly to be utilized in the separation of minerals from their ores by the employment of selective agglomerating, stratifying, or segregating agents.

As is recognized in the art, it is desired frequently to accomplish a selective separation of desired minerals from their ores, such separation being selective either as to the kind of mineral to be taken from ore containing a plurality of minerals, as to size or quality of the mineral content desired to be taken, as to the proportion and amount of mineral it is desired to withdraw, and as to divers and variable factors existing by virtue of the differences between different ores, variations in an ore, and other causes and conditions. For example, in the concentration and purification of graphite and molybdenite ores it frequently occurs that these minerals are found in association with mica or other minerals, which other minerals are useful for some purposes—and it may be desirable to recover them—or which other minerals may be usefully employed if left in association with the graphite or molybdenite, or which minerals it may be necessary to separate absolutely from the graphite or molybdenite in order to render the latter in proper condition for certain uses.

Likewise, due to variations in the richness of ores, or in variations in their refractory properties, variations in the nature, form and amount of matrix and gangue material as well as other variations in the nature and properties of the ore, it becomes desirable to vary the treatment in the process of separation or concentration in order to operate at the highest efficiency.

Furthermore, in the utilization of surface tension or froth methods of separating desired values out of a prepared pulp it is of importance that the floated values be removed rapidly from the surface of the flota-

tion body, and it is also of importance that any of the desired values which may be carried below the surface of the flotation body, due to their being surrounded or held in the gangue material, be freed and permitted to seek the surface.

In a copending application #281,017 filed March 6, 1919, in which I claim a process, I have described an apparatus in which certain of the features of the apparatus constituting the subject matter of the present application are included. As to such features this application constitutes a continuation of said prior application. Moreover, in my copending application on process of ore separation, S. N. 317,855, filed August 16, 1919, I have described and claimed a process which may be practiced by utilization of the apparatus constituting the subject matter of this application.

It is the general purpose of my present invention to provide an apparatus, the use of which will contribute to a high percentage of recoveries of the desired minerals, and also accomplish rapid handling of the ore, and possess large capacity. It is likewise the purpose of my invention to provide an apparatus which permits of a selectively variable treatment of the ore such as to accommodate a wide diversity of conditions in the ore and enable at all times the highest recovery at the highest efficiency.

Another object of my invention is to provide an apparatus by virtue of which selection may be made among the various mineral contents of ores for the recovery of a desired mineral, or desired minerals, either separately or in association.

Another object of my invention is to provide an apparatus by the utilization of which an early differentiation and segregation of divers mineral contents of ore and the recovery and selection of desired contents practically as soon as any segregation or artificial differentiation between the contents are accomplished.

A further object of my invention is to provide an apparatus whereby the operations of selection and extraction of a desired mineral content or contents may be carried on continuously and concomitantly with the operations of freeing, segregating and separating divers metal contents of the ore, and whereby assorting of the desired values as to size, weight, specific gravity or other characteristics, may be accomplished.

- A further object of my invention is to provide an apparatus whereby any and all desired values may be extracted from ores in a single handling of the material.
- 5 A further object of my invention is to provide an improved apparatus useful particularly for the recovery of graphite, molybdenite and other minerals from graphite and molybdenite ores.
- 10 Other and further objects of my invention will be obvious or pointed out herein and in the appended claims and illustrated in the accompanying drawings forming a part of this application.
- 15 I will describe my improved apparatus as utilized in the separation or concentration of such ores as graphite ore or molybdenite ore, but it will be understood that the apparatus is designed for other uses and on other ores which are various both as to kind and form, and that the invention may be embodied in an apparatus differing in various particulars and degrees from that herein disclosed.
- 20 Described generally, my invention comprises a pulp handling device having a wall over which the ore in a prepared form may be transmitted for the purpose of accomplishing segregation, stratification, or ag-
- 25 gleration of the desired contents of the ore in conformity with characteristics with which they are naturally or artificially endowed. Disposed in association with the pulp supporting wall are selecting devices capable of removing constituents of the pulp transmitted over the wall. These selecting devices may be in the form of suction nozzles adjustable relatively to the pulp supporting wall, together with means for
- 30 inducing a pneumatic suction through said nozzles, by force of which constituents of the pulp may be lifted out of or off of the mass. The invention contemplates also a pulp handling device in which the pulp supporting wall is pervious to fluid either gaseous or liquid, which may be discharged through the wall into the pulp supported thereon so as to produce a working of the pulp and a freeing of the desired constituents so that the latter under the combined influence of the fluid percolating through the pulp and the suction induced through the separating devices, may be readily separated out of and off of the pulp and removed from association therewith. The invention contemplates also that there may be a plurality of these selecting devices adjustable relative to the pulp supporting wall so that the pulp stream transmitted over the latter may be brought under their respective influences at different times and periods during the process of segregation or agglomeration in the pulp stream, so that there may be accomplished a classifying selection
- 35 of the desired values.
- The invention contemplates, moreover, the employment of a selecting device operating by pneumatic suction in association with a launching device and a flotation body in such fashion that the values separated out of the pulp by the flotation body and sustained on the surface thereof may be rapidly lifted therefrom, so that the capacity of the flotation body is greatly augmented and it is enabled to take care of the increased volume of pulp supplied to it by the pulp handling device of my improved construction. To further assist in the effectiveness of the suction device associated with the flotation body, I provide means for injecting gaseous fluid in such relationship to the flotation body and the concentrates supported thereon as to form a suction or stratum of gas between the flotation body and the supported concentrates. By such means the tension upon the flotation body is relieved to a degree, and the withdrawal of the concentrates by the suction device assisted.
- The invention will be understood more specifically by reference to the accompanying drawings, in which Figure 1 represents a largely diagrammatic view of one form of my improved apparatus.
- Figure 2 represents a fragmentary detail in the nature of a part top or plan view of the pulp supporting wall.
- Figure 3 is a detail in the nature of an elevational section illustrating the association of pulp handling device, flotation body and selecting device.
- Figure 4 is a detail view illustrating another embodiment of this feature of the invention, and
- Figure 5 is a detail in the nature of a fragmentary top view of a pulp arresting or lifting device.
- Reference being had to these drawings by means of the reference characters applied, it will be understood that the numeral 1 designates generally a mixing or reducing machine in which ore reduced to a proper mesh may be mixed with certain characterizing or differentiating agents whereby discrete particles of like mineral may be endowed with characteristics tending to cause their agglomeration in formative masses, or their stratification separate from particles of other material, thus accomplishing a segregation of different mineral contents in the ore. Where the apparatus is employed in a process of separation by the surface tension method or by flotation, it is to be understood that a characterizing agent is employed which has a preferential affinity for the desired mineral content of the ore, and at the same time is non-assimilating or immiscible with the liquid which is utilized to provide the flotation body. Such a method of treatment may consist of wetting the ore

slightly, introducing the slightly moistened ore into a grinding mixture of oil and water and then agitating the ore and launching same on to the surface of a flotation body, 5 said agitation being accomplished by disseminated gases being introduced into the ore through the wall of the launcher. From the device 1 the ore is discharged in the form of a pulp or in comminuted form upon a 10 launder 2, from which it is advanced to a distributing device 4. In association with the distributing device 4 is arranged a pulp handling device 5. This device may be constructed in accordance with the description 15 in my copending application on pulp handling device. It may include a lower wall 6, side walls 7, and a pulp handling wall 8, said walls being combined in such fashion as to provide a receptacle into which fluid, 20 either gaseous or liquid, or both, may be introduced by conduits 9, said receptacle being adapted also for adjustable support in association with a suitable flotation body 10.

As illustrated, the pulp supporting wall 25 8 of the pulp handling device may be formed in the fashion of a succession of steps or stages 8^a so that the pulp on the device may be transmitted from one stage on to the next. This progressive movement of the pulp or 30 ore over the pulp supporting wall may be accomplished by gravity, when the pulp supporting wall is inclined, or may be accomplished by the force of streams of fluid emitted through the apertures such as those 35 indicated at 11, in the pulp supporting wall. Other apertures, such as those indicated at 12 (Fig. 3), may be provided in the pulp supporting wall for the purpose of permitting the egression of fluid from the interior 40 of the pulp handling device into the pulp supported on the wall 8. It will be understood that the fluid thus injected into the pulp will have the effect of working or enlivening it in such manner as to contribute 45 to the freeing of the particles of the desired contents of the ore from other material in the pulp, and permitting the segregation of the differently characterized contents into different strata, and the agglomeration of 50 the discrete particles which are endowed with that capacity. Adjustably associated with the pulp handling wall 8 are one or more selecting or removing devices, designated by numerals 14, 14^a, and 14^b. Said selecting or removing devices may be in the 55 form of suction nozzles as shown, having communication with conduits 15. Suction through the nozzles and conduits may be induced by suitable means such as the fans 60 16. In the device illustrated the nozzles are rendered adjustable by means of telescoping joints, but, of course, other expedients may be utilized for this purpose. In the form illustrated it is seen that the removing devices 14 and 14^a are associated with portions

of the wall 8 above the surface of the flotation body 10, and that the nozzle 14^b is associated with the surface of the flotation body and with a portion of the wall 8 which is submerged below the flotation body. 70

The several stages of the pulp handling device may be equipped with the apertured separating members after the fashion disclosed and claimed in my co-pending application on pulp handling device, and shown 75 for the purpose of illustration in Fig. 2 herein. It will be sufficient for the present purpose to explain that in the construction referred to, one or more of the stages 8^a are provided with the apertured terminal separating members 8^b which may be in the form of a foraminous plate, or a member of comb-like or serrated form, disposed at the forward limit of the stage in position such as to receive the stream of pulp from the stage. 80 These separating members 8^b are disposed overhanging the next adjacent stage so that pulp is transmitted from them on to such next stage in the progressive movement of the pulp stream. As illustrated in Figs. 1 85 and 2 it may be desirable to associate the nozzles 14 and 14^a with certain of the separating members 8^b, the adjustability of the nozzles permitting any desired positioning relative to the separating members. 90

The arrangement of the nozzle 14^b, which is associated with the flotation body is such as to permit its withdrawing from the surface of the flotation body material separated out of the pulp by surface tension separation or by flotation on the flotation liquid. The position of the nozzle, therefore, is such as to permit the movement of material on the surface of the flotation liquid into the nozzle. In the form illustrated in Fig. 3 the forward wall of the nozzle extends down to or 100 into the flotation liquid, and forms a dam for arresting the movement of the material rafted over the surface of the flotation liquid, and for detaining it in a location 110 where the suction induced through the nozzle will be effective upon it. In the form illustrated in Fig. 4 a grating or foraminous member 17 is adjustably supported on or adjacent the nozzle and adapted to project 115 into the flotation liquid in such fashion that it lies in the path of the material floated upon the liquid from the pulp handling device, and operates to guide such material to the effective zone of the nozzle. 120

A fragmentary top view of one form of the foraminous member 17 is shown in Fig. 5, wherein it is seen it is provided with apertures such as to permit the passage through it of the unagglomerated material which 125 sinks in the flotation liquid.

As will be seen in Figs. 1, and 3, the lower or forward extremity of the pulp supporting wall extends into the flotation liquid in such manner that a wedge-shaped portion of 130

the liquid extends over and above it as at 18.

The apparatus above described has the capacity of functioning upon a properly prepared pulp, as referred to above, in the following fashion:

The pulp being properly prepared and distributed upon the pulp handling device from the distributor 4, it is moved progressively along the pulp supporting wall under 10 the influence of gravity or under the influence of the fluid streams emitted through the apertures 11. This progressive movement of the pulp over the pulp handling device is attended with a working or enlivening of 15 the pulp, due to the passage of the fluid through it from the apertures 11 and 12, and due also to the undulating of the pulp in passing from stage to stage. This working or enlivening of the pulp has the effect 20 of permitting the differently characterized discrete particles to segregate themselves into distinct strata, by virtue of the characteristics which they naturally posses or the characteristics with which they have 25 been endowed in the preparation of the pulp. Where agglomerating agents have been utilized in the preparation of the pulp for the characterizing of one or more of the desired constituents, this working of the pulp 30 will operate to free the particles from the pulp mass, permit their moving into juxtaposition and agglomerating into formative masses.

In the event the preparation of a pulp 35 is designed to produce a froth forming mixture, as may be desired in the separation of metallic or metalliferous ores, this working of the pulp over the stepped surface and the injection of gaseous fluid thereinto will produce a surface stratum of froth effective to carry the particles of the desired values. Because of the fact that the apparatus handles the pulp in the form of a thin sheet or ribbon this froth is quickly and easily produced, without the expenditure of power 45 now required. This working of the pulp is further contributed to by the separating members 8^b, when present, which operate to retain for a period the formative masses of 50 the agglomerated constituents while permitting the more fluid and smaller unagglomerated content of the pulp to pass through the slots or apertures. As stated, this handling of the pulp produces a segregation 55 of the differentiated constituents, the agglomerated or froth carried materials occupying the stratum at the surface of the pulp stream. The progressive movement of the pulp stream carries the material in this 60 stratified form into the zones of effectiveness of the respective nozzles 14 and 14^a successively. The suction induced in the said nozzles will be effective to withdraw the desired materials from the surface of the pulp,

and to carry them to a proper place of disposal.

The formative masses into which the discrete particles coalesce through the capacity given them by the agglomerating agent with which they are filmed, are buoyant, and 65 have spongy, plastic, elastic and flocculent properties,—and thus come the agglomerated minerals to have a lower specific gravity than the gangue in which they are found, and therefore when moved to the top of a 70 stratum of gangue it will have a tendency to remain there until removed. These properties contribute to the ability of the suction device to remove the agglomerated masses 75 from the surface of the pulp. In this action 80 the suction nozzles are aided by the means for injecting gaseous fluid into the pulp, as the air which is forced into the pulp through the apertures 12 of the pulp supporting wall, after percolating up through the more or 85 less fluid under-strata in the pulp, reaches the more coherent elastic and plastic agglomerated stratum at the top, and tends to define more sharply the line of cleavage between the agglomerated stratum and the 90 portion of the pulp upon which it rests, thus aiding in the removal of the agglomerated values. Moreover, the presence of this mobile gas below the agglomerated masses 95 contributes in part to the establishing of a definite current into the suction nozzle, by which current the movement of the agglomerated material is accomplished.

In the course of its continued progressive movement the pulp stream is directed to the flotation body. As seen in Fig. 3, the portion of the flotation body forming the water wedge 18 tends to extend upwardly in the down-coming pulp and assists in separating or splitting off the desired stratum, or the values endowed with the non-assimilating or floatative capacity, from the tailings or reject materials which are filmed or saturated with the agent which is assimilating with the flotation liquid. The material which is characterized by a non-assimilating film is moved into the operative zone of the nozzle 14^b, by which it is lifted or withdrawn by suction from the surface of the flotation body, while the tailings continue to travel down the surface of the pulp supporting wall below the flotation body and are discharged at the forward or lower terminus of the pulp handling device. This separation by surface tension or flotation may be utilized as a final operation of the device to recover the modicum of the desired content remaining in the pulp after the submission of the pulp to the operation of the withdrawing members 14 and 14^a. Or this separation on the flotation liquid may be the sole separation operation in the employment of the device. It has been explained above how the

forward portion of the nozzle in Fig. 3 and the members 17 in Fig. 4 operate to limit the extent to which the floated values may be rafted over the surface of the flotation body.

5 The gaseous fluid emitted through the apertures 12 of the portion of the pulp handling device submerged in the flotation liquid works through the pulp remaining on the pulp supporting wall, freeing all the particles having the non-assimilating film, and permitting their rising to the surface of the flotation body. The gas percolates up through the flotation liquid constantly, and tends to provide an air stratum between the 10 surface of the flotation body and the concentrates supported thereon, thus contributing to the function of the nozzle in lifting the concentrates from the surface of the flotation body, and rendering such withdrawal 15 of the concentrates more facile and complete. This lifting effect upon the floating values by the gas injected beneath them and the pneumatic suction from the nozzle tends to relieve the strain upon the surface film of 20 the flotation body, and also contributes to the very rapid removal of the concentrates from the flotation body so that the latter is not over-loaded by the rapid discharge of 25 pulp from the pulp handling device.

30 From the foregoing description of certain functions in this apparatus it will be seen that the device contributes to rapid handling of the prepared pulp, whereby the apparatus possesses a great capacity. It is to be observed also that it produces such thorough 35 working of the pulp as to permit the withdrawal of the entire desired content at a single handling, the several selecting devices 14, 14^a and 14^b becoming effective upon 40 the progressively moving pulp stream at different periods, one after the other, whereby the values freed and segregated or agglomerated in the pulp stream during its movement from one to the next of said selecting 45 devices, are immediately removed. The device in this fashion provides a means whereby a classified separation of the concentrates from the pulp may be made, thus eliminating 50 the necessity of further handling of the concentrates for the purpose of such classification.

Having thus described my invention, what I claim is:

1. An apparatus for use in concentrating 55 ores and the like and comprising a container for a flotation liquid, a launching device having a pervious launching member adapted to extend within said container in such manner that a portion of the flotation liquid 60 extends over the lower end of the launching member as a wedge-shaped cross-section, means to supply gas under pressure beneath said member whereby minute streams of gas are caused to percolate upwardly through 65 said member and through the wedge-shaped

cross-section of the flotation liquid, and a suction device having the intake thereof effective adjacent the place at which the concentrates are launched upon the flotation liquid and having a portion comprising a 70 dam to limit the travel of the concentrates, on the flotation liquid.

2. In an apparatus for concentrating ores, in combination, means for preparing a pulp by differentially filming the values and reject material, a pulp supporting wall arranged for the progressive movement of pulp thereover, and removing devices operating through pneumatic suction and adjustable toward and from said wall and effective at different zones spaced apart in the direction of the movement of the pulp.

3. In an apparatus for concentrating ores, in combination, means for differentially filming the values and reject material, a 85 pulp supporting wall arranged for the progressive movement of pulp thereon, said wall being formed to produce a working of the pulp in its progressive movement, means associated with said wall for effecting the percolation of a gas upwardly pulp moving thereon, and suction devices disposed in association with said wall for removing by suction portions of the pulp in 90 the course of its progressive movement over 95 a selected portion of the wall.

4. A device for concentrating ores, in combination, means for differentially filming the values and reject material, a pulp supporting wall arranged for the progressive movement of pulp thereon, said wall including devices whereby a working of the pulp is accomplished in the course of its progressive movement, means associated with said wall for injecting fluid into pulp 100 thereon during its progressive movement, and suction devices associated with said wall for the removal of pulp therefrom in restricted zones, said suction devices being 105 spaced apart in the direction of the pulp's 110 progressive movement.

5. In a device for concentrating ores, in combination, means for differentially filming the values and reject material, a pulp supporting wall arranged for the progressive movement of pulp thereon, said wall including devices whereby a working of the pulp is accomplished in the course of its progressive movement, means associated with said wall for injecting fluid into pulp 115 thereon during its progressive movement, and suction devices associated with said wall for the removal of pulp therefrom, said suction devices being selectively adjustable relative to the wall and to each other to 120 vary their zones of removal.

6. In a device for concentrating ores, the combination of means for differentially filming the values and reject material, a pulp supporting wall forming a series of spaced 130

- apart stages arranged to deliver pulp from one on to another thereof, an apertured separating member disposed to receive pulp from one stage and deliver it to the next, and suction devices associated with the apertured separating member exclusively and effective to remove portions of pulp therefrom. 45
7. In an apparatus for concentrating ores, 10 in combination, means for differentially filming the values and reject material, a pulp supporting wall arranged in the form of a plurality of stepped stages with serrated margins disposed in position to deliver pulp in progressive movement from one to another thereof and suction operating means associated with said wall for removing portions of the pulp therefrom. 50
8. In an apparatus for concentrating ores, 20 in combination, means for differentially filming the values and reject material, a pulp supporting wall arranged in the form of a plurality of stepped stages disposed in position to deliver pulp in progressive movement from one to another thereof and a plurality of devices each effective separately upon a different stage for removing portions of the pulp therefrom. 55
9. In an apparatus for concentrating ores, 30 in combination, means for differentially filming the values and reject material, a pulp supporting wall arranged in the form of a plurality of stepped stages disposed in position to deliver pulp in progressive movement from one to another thereof and a plurality of devices each associated with a different stage and adjustable toward and from the same and effective to remove portions of pulp therefrom. 60
10. In an apparatus for concentrating ores, 40 in combination, means for differentially filming the values and reject material, a pulp supporting wall arranged in the form of a plurality of stepped stages disposed in position to deliver pulp in progressive movement from one to another thereof and means adjustable toward and from a stage and operable effectively to remove portions of pulp therefrom. 65
11. In an apparatus for concentrating ores, 50 in combination, means for differentially filming the values and reject material, a pulp supporting wall arranged in the form of a plurality of stepped stages disposed in position to deliver pulp in progressive movement from one to another thereof and a device adjustable for association selectively with said stages and operable effectively to remove portions of pulp therefrom. 70
12. In an apparatus for concentrating ores, 60 in combination, means for differentially filming the values and reject material, a pulp supporting wall arranged in the form of a plurality of stepped stages disposed in position to deliver pulp in progressive movement from one to another thereof and a plurality of suction operated devices associated with said stages and effective to remove portions of pulp therefrom and adjustable to vary their zones of effectiveness. 75
13. An apparatus for concentrating ores comprising in combination a flotation body, means for artificially differentiating different components of the ore with reference to the flotation body, a launching device associated with the flotation body and said last mentioned means and having a pulp supporting wall arranged above the flotation body and constructed to accomplish manipulation of pulp and its progressive movement to the flotation body from said last mentioned means, and selectively operable means cooperatively associated with said pulp supporting wall and the surface of the flotation body and operated by suction to accomplish withdrawal of portions of pulp from said wall and said surface. 80
